DRAFT GEAR

James R. Cardwell, Barrington, Ill.

Application March 16, 1943, Serial No. 479,359

16 Claims. (Cl. 213—32)

1

This invention relates to draft gears for vehicles, and more particularly for railway cars.

One of the objects of the invention is the provision of a new and improved resilient draft gear provided with friction means for increasing the capacity of the gear.

Another object of the invention is the provision of a new and improved draft gear of the wedge friction type having novel means for preventing splitting or bursting of the chambered follower during the final compressive movement of the gear, or when the gear goes solid.

Another object of the invention is the provision of a new and improved gear that is simple in construction, composed of few moving parts, easily assembled, and that is inexpensive to manufacture.

Other and further objects and advantages of the invention will appear from the following description, taken in connection with the accompanying drawings, in which

Fig. 1 is a longitudinal section of a portion of a railway car showing the draft gear in position thereon;

Fig. 2 is an end elevation of the gear;

Fig. 3 is a section on the line 3—3 of Fig. 1;

Fig. 4 is a section on the line 4—4 of Fig. 1;

Fig. 5 is a view similar to Fig. 1, but showing a modified form of construction;

Fig. 6 is an end elevation of the gear shown in Fig. 5;

Fig. 7 is a section on the line 7—7 of Fig. 5;

Fig. 8 is a section on the line 8—8 of Fig. 5; and

Fig. 9 is a section on the line 9—9 of Fig. 5.

Under war conditions, which now obtain in almost all countries of the world, the demand for ferrous material in all phases of war equipment is such as to necessitate the elimination of unnecessary metal in all manufactured articles, and the reduction in weight of all equipment to a minimum. But the reduction in the amount of metal ordinarily used in draft gear housings reduces the strength of those housings to such an extent that splitting or breaking of the housing is likely to occur on compression unless provision is made for preventing it, especially in the type of gear employing friction wedge means for increasing the capacity of the gear.

The present invention seeks to meet these requirements and remedy this difficulty by providing a draft gear of minimum weight which is reinforced by a collar or flange around the open end of the gear housing, and also by providing means for wedging the open end of the housing

2

radially inwardly during the final compressive movement of the gear.

Referring now to the drawings, the reference character 10 designates, generally, a portion of a railway car having an end sill 11 and a pair of center sills 12, 13. The center sills are preferably, though not necessarily, of channel form, arranged back to back, and are spaced apart. An upper plate 14 extends across above the center and side sills, and is rigidly connected to the flanges 15, 16, of the center sills, as shown in Fig. 4. The front end of this plate extends over and engages the upper flange of the end sill 11, to which it is rigidly connected. A lower plate 140 extends across beneath said center sills, and is rigidly connected to the flanges thereof, as by means of rivets. This plate is directly beneath the plate 14, and has its forward end extended beneath the lower flange of the end sill 11 and rigidly secured thereto. The ends of the center sills extend forwardly to the end sill and are rigidly connected to the web thereof in any suitable manner, as by means of the angle bars 17, 18 (see Fig. 4).

25 The end sill 11 is provided with an angular opening 19 through its web portion, through which an enlarged portion 21 of a drawbar 22 is adapted to extend, as will presently appear. The enlarged portion 21 is angular in cross-section to correspond with the opening 19 for preventing rotation of said bar, and, in the form shown, it is rectangular in cross-section. Rigidly mounted on the face of the end sill 11 is a reinforcing plate 23, having a rectangular opening therein 30 which registers with the opening 19. The plate 23 is secured to the outer face of the end sill in any suitable manner, as by welding, as shown at 24.

An abutment wall, in the form of a channel member 25, extends between the center sills. The flanges of the channel member extend forwardly, that is, toward the adjacent end of the car. The member 25 is rigidly connected at each end to the webs of said sills by suitable flange members 45 or brackets 26, as shown in Fig. 1. One flange of each angular member or bracket 26 is rigidly secured to the web of the adjacent center sill, as by means of rivets 27, and the other flange is secured to the web of the abutment wall 25 as 50 by means of the rivets 28. The abutment wall 25 is provided axially thereof with an angular opening 29, which is in axial alinement with the opening 19 in the end sill. A follower block 31 seats against the back or web portion of the abutment wall 25, and is also provided with an open-

ing 32 in alinement with the openings 29 and 19. The openings 29 and 32, as well as the opening 19, are angular, and, in the form of construction shown, are rectangular in form and slightly larger than the cross-section of the drawbar 22 which extends therethrough.

The drawbar 22 has integral therewith, at its forward end, a coupler member 35 in the form of a hook, which is adapted to engage a coupler link (not shown), and its opposite end is extended beyond the abutment wall 25 and is screw-threaded, as shown at 36. A suitable draft gear cushioning member 37 is mounted on the inner end of the drawbar 22, as will now be described.

This draft gear or cushioning device 37 comprises an open ended follower or gear housing 38, which opens rearwardly and has its end wall 39 seated against the follower block 31. For convenience of description the direction toward the hook end of the draft gear will herein be referred to as forwardly and toward the opposite end as being rearwardly. This follower 38 is angular in cross-section, as shown in Fig. 3, and in the form of construction selected to illustrate one embodiment of the invention it is hexagonal and provided on its interior with hexagonal friction surfaces 40. Suitable friction shoes 41, 42 and 43 are provided for engaging these friction surfaces. Each of these shoes is provided with an outer angular face 44, which is adapted to engage two adjacent friction surfaces 40 of the chambered follower 38.

Each of the shoes is provided on its inner surface with an inclined wedging face 45 (see Fig. 1), which is adapted to be engaged by a corresponding inclined wedging face 46 of a wedge member 47. The wedge member 47 has three inclined or wedging faces adapted to engage the corresponding inclined faces of the shoes 41, 42 and 43 for forcing the shoes radially outwardly into frictional engagement with the friction surfaces 40 of the chambered follower 38.

Suitable means are provided for resiliently resisting the free forward movement of the shoes into the chambered follower 38, so that when the wedge member 47 is forced into the follower it will force the friction shoes into said follower and also radially outward into frictional contact with the friction surfaces 40 of the followers. As shown in Fig. 1, a plurality of springs 48, 49, are employed for this purpose. Any desired number of springs may be used, but, as shown, two springs are employed. These springs are telescoped and concentric and seat against the end wall of the follower at their forward ends, and at their rear ends engage a spring seat 51, having an axial opening 57 provided on its inner side with an inclined wedging face 52 for each wedge. Each wedge face is adapted to engage a corresponding inclined wedging face 53 on the corresponding wedge member, as shown more clearly in Fig. 1 of the drawings.

A suitable follower is provided for engaging the wedge member 47, and, in the form of construction shown, a follower 54 is employed for this purpose. The follower 54 is provided with an axial internally threaded opening which is adapted to engage the threaded end 36 of the drawbar. The follower is provided with a hub 55, which extends through an axial opening 56 in the wedge 47 for positioning the wedge. This wedge is also provided with an axial opening 57, of less diameter than the opening 56, and through which the inner end of the drawbar 22 extends. The follower 54 is also provided with a hub 58,

extending toward the center of the car, which has alined transverse elongated openings 59 therethrough adapted to be turned to position into alinement with a corresponding transverse opening 59^b through the threaded end of the drawbar 22 for adjustably receiving a cotter pin 61 for preventing relative rotation of the follower and drawbar. The hub 58 may also be castellated at its end, as shown at 59^a, for receiving the cotter pin in event the openings or slots 59 are not long enough to compensate for the wear of the parts. The slots 59^a permit further adjustment of the follower 54 along the threaded end of the drawbar, if it becomes necessary to take up additional wear on the wedges or on the shoulder 90 of the drawbar hook. The follower 54 has, on the side adjacent the hub 58, radially extending reinforcing ribs 50 integral with the hub 58 and rim 60 on said follower.

The coupler 35 may be in the form of a hook 62, as shown in Fig. 1, and this hook is provided with a keeper 63 the inner ends of which engage in an elongated slot 64, which permits the keeper to be turned above the hook and to drop onto a connecting link when the car is coupled to the next adjacent car, as is usual in such constructions.

Suitable means are provided for biasing or wedging the open end of the housing radially inwardly during the final compressive movement of the gear for counteracting excessive expansive strains on the housing tending to burst the same. In the construction shown, this is accomplished by providing the inner follower 54 with a depression 66 having an inclined wedging surface 67 extending inwardly from the outer periphery of the follower. This inclined surface is adapted to engage a corresponding inwardly beveled surface 68 on the open end of the chambered follower 38, so that as the draft gear or cushioning device nears the limit of its compression the inclined surface 67 will engage the inclined surface 68, tending to force the open end of the follower radially inwardly, thereby preventing a bursting strain on the open end of the follower or housing 38. This is considered an important feature of the invention, because as the draft gear reaches the limits of its compression—as under abnormal loads or under abnormal conditions—enormous radial force tending to burst the follower is developed.

The form of construction shown in Fig. 5 differs from that shown in Fig. 1 in that, instead of using springs for resiliently resisting the movement of the friction shoes 41^a, 42^a and 43^a into the chambered follower 38^a, a block of rubber 65 is employed for this purpose. The rubber 65 is preferably, though not necessarily, annular and diamond or lozenge-shaped in cross-section, as shown in Fig. 5. In this form of construction it is not necessary to employ a spring plate corresponding to the spring plate 51 of Fig. 1, so that this plate is omitted, and the rubber block 65 seats directly on the friction shoes 41^a, 42^a and 43^a. Since the remaining portion of the construction is substantially the same as that already described, it is not thought necessary to repeat it.

In this form of construction it will be evident that when the rubber is compressed it will be forced to flow into the unoccupied portion of the chambered follower, thereby gradually increasing the resistance to the movement of the friction shoes into the chambered follower.

In both forms of construction the resilient members more strongly resist the compression of

the gear as the compressing force increases; and in both forms of construction these resilient members restore the parts to normal position upon release of the compressive force.

It will be noted that in both forms of construction the gear is positioned by the drawbar, which extends through alined angular openings in the end sill and abutment member. It will also be seen that the drawbar is extended and becomes a part of the draft gear or cushioning device.

In operation, any pulling force, whether a steady or a sudden violent force on the coupler hook 62, will be transferred directly to the draft gear where any shock will be partially absorbed by the springs and by the frictional resistance of the wedge mechanism. The remainder of the force will, by the reaction of the gear on the abutment 25 and associated parts, be expended in drawing the car forward.

Should the tensile force on the drawbar be sufficient to almost close the gear, or should a sudden and violent pull be of such intensity as to all but close the gear, the internal wedging faces 67 of the follower 54 will engage the external inclined wedging faces 68 of the follower or housing 37 and cam the latter inwardly, thus preventing excessive expansion of the open end of the latter.

It is thought from the foregoing, taken in connection with the accompanying drawings, that the construction and operation of my device will be apparent to those skilled in the art, and that changes in size, shape, proportion and detail may be made without departing from the spirit and scope of the appended claims.

I claim as my invention:

1. In a draft gear, a chambered follower having an interior friction surface, friction shoes engaging said surface, a wedge member engaging said shoes, resilient means for resiliently resisting the inward movement of said shoes along said surface, a follower engaging said wedge member, and cooperating means on said last-named follower and the adjacent end of said chambered follower for resisting the radial expansion of said chambered follower during the final compressive movement of said gear.

2. In a railway car, a pair of center sills, an end sill rigidly connected to said center sills, all of said sills constituting conventional parts of the car frame, an abutment member having rigid connection with said end sill and being spaced therefrom at substantially the same level therewith, a drawbar having a coupler on its forward end extending through alined openings in said front sill and abutment member, a friction draft gear surrounding the rear end of said drawbar, and means on said rear end of said drawbar to cooperate with said abutment member for compressing said draft gear in response to forward movement of the drawbar.

3. A drawbar having a coupler member on one end and a friction draft gear on the other end of said drawbar, said draft gear comprising an open ended chambered follower and an end follower, wedge mechanism in the open end of said chambered follower for absorbing tensile shocks applied to said drawbar, and cooperating cam means for forcing the open end of said follower radially inwardly during the final closing movement of the gear when a pulling force is applied to said drawbar.

4. In a railway car, an end sill, a pair of center sills spaced apart and having their forward ends rigidly connected to said end sill at substantially

the same level as the end sill, an abutment member at substantially the same level parallel with said end sill and spaced therefrom and rigidly connected to said center sills, said end sill and abutment having alined angular openings therethrough, a drawbar having a coupler member on its forward end provided with angular portions extending through said openings for preventing rotation of said drawbar, a friction draft gear on the rear end of said drawbar, means on said rear end of said drawbar to cooperate with said abutment member for compressing said draft gear in response to forward movement of the drawbar, means for compensating for frictional wear on the parts of said gear, and means for restoring the parts to normal position upon release of said gear.

5. A draft gear comprising a chambered follower having an inwardly beveled open end and having interior friction surfaces, friction shoes engaging said surfaces, a wedge member for forcing said shoes into said follower and radially outward into frictional engagement with said friction surfaces, resilient means for yieldingly resisting the inward movement of said shoes, a follower engaging the outer end of said wedge member, and means associated with said gear and last-named follower for compressing the gear upon applying a force to said means, said follower having a wedging face adapted to engage said beveled face during the final closing movement of said gear for resisting excessive expansion of the open end of said chambered follower.

6. A draft gear comprising a chambered follower having an inwardly beveled open end, a cooperating follower having an inclined wedging face adapted to engage said beveled end for forcing the same radially inwardly upon abnormal compressive movement of said gear, friction mechanism between said followers and adapted to engage said chambered follower when the gear is compressed, and resilient means for resisting the compression of said gear and for returning the parts to normal position after release.

7. A draft gear comprising a pair of followers normally spaced apart, one of said followers being chambered with the open end turned toward the other follower and having inwardly beveled wedging faces, friction shoes engaging the inner walls of said chambered follower, wedge means engaging said shoes and the other follower, inclined wedging faces for engaging said beveled faces for biasing the open end of said follower radially inwardly upon abnormal compression of the gear, and means for restoring the parts to normal position after release.

8. In a device of the class described, a drawbar having a coupler hook on one end and its opposite end threaded, a follower adjustably mounted on the threaded end of said drawbar, a chambered follower having a closed end and an open end adjacent to but spaced from said first-named follower, friction mechanism within said chambered follower frictionally engaging the interior wall of said last-named follower, wedge means engaging said mechanism, resilient means for restoring the parts to normal position after release, and cooperating means on said followers for biasing the open end of said second-named follower radially inwardly immediately prior to the closing of said gear under compression.

9. In a draft gear, a pair of followers spaced apart, one of said followers being hollow with an open end turned toward the other follower, wedging and friction mechanism in said hollow

follower tending to expand said open end radially outwardly when the gear is compressed, and means for biasing the open end of said follower radially inwardly during the final compressive movement only of said gear.

10. In a railway car having an end sill and a pair of spaced apart center sills rigidly connected to said end sill, an abutment rigidly connected to said center sills and parallel with the adjacent end sill and in spaced relation therefrom at substantially the same level therewith, a drawbar extending through openings in said end sill and abutment member, the outer end of said drawbar having a coupler member integral therewith and having screw threads on its inner end, a follower threaded on the screw threaded end, a chambered follower having an open and a closed end and through which said drawbar extends, a follower block between said closed end and said abutment, friction shoes having wedge faces engaging the interior of said chambered follower, a spring seat engaging said shoes, resilient means between said spring seat and the closed end of said follower, a wedge member engaging wedging faces on said shoes and engaging the follower threaded on said drawbar, and plates secured to said end and center sills above and below the level of said drawbar.

11. In a railway car, an end sill, a pair of center sills spaced apart and having their forward ends rigidly connected to said end sill, an abutment member parallel with said end sill at substantially the same level therewith, and spaced therefrom and rigidly connected to said center sills, said end sill and abutment having aligned angular openings therethrough, a drawbar having a coupler member on its forward end provided with angular portions extending through said openings for preventing rotation of said drawbar, a friction draft gear on the rear end of said drawbar, means on said rear end of said drawbar to cooperate with said abutment member for compressing said draft gear in response to forward movement of the drawbar, means for compensating for frictional wear on the parts of said gear, and spring means for restoring the parts to normal position after release.

12. A drawbar having a coupler member on one end and a friction draft gear on the other end of said drawbar, said draft gear comprising an open ended chambered follower and an end follower, wedge mechanism in the open end of said chambered follower for absorbing tensile shocks applied to said drawbar, cooperating cam means for forcing the open end of said follower radially inwardly during the final closing movement only of the gear when a pulling force is applied to said drawbar, and an annular block of rubber lozenge-shaped in cross-section for restoring the parts to normal position when said gear is released after compression.

13. In a railway car, a pair of center sills, an end sill at substantially the same level rigidly connected to said center sills, an abutment member at substantially the same level having rigid connection with said end sill and spaced therefrom, a drawbar having a coupler on its forward end extending through aligned openings in said end sill and abutment member, a friction draft gear surrounding the rear end of said drawbar,

said draft gear comprising friction and wedging mechanism and a rubber block engaging portions of said mechanism for restoring the parts to normal position upon release after compression, and means on said rear end of said drawbar to cooperate with said abutment member for compressing said draft gear in response to forward movement of the drawbar.

14. A draft gear comprising a casing angular in cross-section and having a plurality of interior friction faces, a plurality of friction shoes each engaging two adjacent friction faces, a wedge member having an inclined wedging surface for each shoe for forcing said shoes simultaneously into frictional contact with the corresponding frictional faces of said casing, a movable follower, a drawbar extending axially through said casing and movable follower, means for resiliently resisting the compression of said gear when tension is applied to said drawbar, said means functioning to restore the parts to normal position upon release, means for preventing excessive radial expansion of said casing during excessive tension on said drawbar, and means including said drawbar for limiting the expansion of said gear.

15. In a railway car, a front sill, a pair of center sills spaced apart and having their forward ends rigidly connected to said end sill, an abutment member parallel with said end sill and spaced therefrom and rigidly connected to said center sills, said end sill and abutment having aligned angular openings therethrough, a drawbar having a coupler member on its forward end provided with angular portions extending through said openings for preventing rotation of said drawbar, a friction draft gear on the rear end of said drawbar, said gear comprising a casing angular in cross-section and having a plurality of friction faces arranged at an angle to one another, a plurality of friction shoes engaging said faces, each shoe engaging two adjacent friction faces, a wedge member having an inclined wedging surface for engaging each shoe, resilient means for resisting the compression of said gear and for returning the parts to normal position after release, a movable follower movable with said drawbar and engaging said wedge member for compressing said gear when tension is applied to said drawbar, and means for resisting radial expansion of said casing during the final compressive movement of said gear.

16. In a draft gear, a hollow member having an inner friction surface, a drawbar extending into said hollow member, wedge means movable with said drawbar for radial expansion against said friction surface, yielding means acting on said wedge means to resist longitudinal movement of said drawbar in one direction relative to said hollow member and to progressively increase the radial pressure of said wedge means in response to said longitudinal movement of the drawbar, and means responsive to said longitudinal movement to engage said hollow member automatically for reinforcement thereof against radial pressure from the wedge means as the limit of said movement is approached thereby to prevent rupture of the hollow member under peak radial pressure.

JAMES R. CARDWELL.
